UNITED STATES PATENT OFFICE

169,927

ANIMAL FIGURE TOY

Neva Iola Broyles, Henderson, Nev.

Application September 3, 1952, Serial No. 21,294

Term of patent 14 years

(Cl. D34—2)

To all whom it may concern:

Be it known that I, Neva Iola Broyles, a citizen of the United States, residing at Henderson, Nevada, have invented a new, original, and ornamental Design for an Animal Figure Toy, of which the following is a specification, reference being had to the accompanying drawing, forming part thereof, in which

The back of the animal figure toy is plain.

I claim:

The ornamental design for an animal figure toy, as shown and described.

NEVA IOLA BROYLES.
